UNITED STATES PATENT OFFICE.

CARL D. PACE, OF OXFORD, ALABAMA, ASSIGNOR OF ONE-HALF TO JOSEPH C. WHEELER, OF ANNISTON, ALABAMA.

STUMP-PULLER.

1,339,666.

Specification of Letters Patent. Patented May 11, 1920.

Application filed July 16, 1919. Serial No. 311,264.

To all whom it may concern:

Be it known that I, CARL D. PACE, a citizen of the United States, residing at Oxford, in the county of Calhoun and State 5 of Alabama, have invented certain new and useful Improvements in Stump-Pullers, of which the following is a specification, reference being had to the accompanying drawings.

10 This invention relates to certain improvements in stump pullers, and it is an object of the invention to provide a novel and improved device of this general character which may be readily and conveniently positioned with respect to the work and which 15 is provided with means whereby the same may be effectively operated to create the requisite pull or strain.

It is also an object of the invention to 20 provide a novel and improved device of this general character including a winding member and a power member, together with means whereby the winding member may be driven by the power member and wherein 25 either of said members may be moved, one independently of the other.

Furthermore, it is an object of the invention to provide a novel and improved device of this general character which is of a 30 foldable type and wherein a tractor or other source of power independent of the device may be employed to create the requisite pulling action.

The invention consists in the details of 35 construction and in the combination and arrangement of the several parts of my improved stump puller whereby certain important advantages are attained and the device rendered simpler, less expensive and 40 otherwise more convenient and advantageous for use, as will be hereinafter more fully set forth.

The novel features of my invention will hereinafter be definitely claimed.

45 In order that my invention may be the better understood, I will now proceed to describe the same with reference to the accompanying drawings, wherein:

Figure 1 is a view in side elevation of a 50 stump puller constructed in accordance with an embodiment of my invention and in operative connection with a stump to be extracted.

Fig. 2 is an enlarged fragmentary view partly in section and partly in elevation 55 illustrating the mounting of the power drum.

Fig. 3 is a fragmentary view partly in section and partly in front elevation of the upper portion of the device as herein embodied.

Fig. 4 is a fragmentary view in rear elevation of the upper portion of the device as herein set forth.

Fig. 5 is a fragmentary view partly in side 65 elevation and partly in section illustrating the coaction of a holding member with a winding member or element.

Fig. 6 is an enlarged sectional view taken substantially on the line 6—6 of Fig. 1. 70

Fig. 7 is a view in side elevation illustrating a stump puller constructed in accordance with a further embodiment of my invention.

Fig. 8 is a fragmentary view in rear 75 elevation of the structure disclosed in Fig. 7, the operating shaft being in section.

As disclosed in Figs. 1 to 6 inclusive, my improved device is mounted upon a pair of transversely spaced runners R arranged 80 substantially in parallelism and having its opposite end portions upturned as indicated at 1 in order to facilitate the travel thereof over the ground. It is preferred that each of the runners R be of channel formation 85 with the open face upwardly directed. It is also preferred that each of the runners R be disposed transversely on a predetermined incline, as illustrated in Fig. 6. By this arrangement the travel of the runner 90 over the ground is materially benefitted and at the same time the machine in its entirety is effectively held against lateral movement and also to hold the runners against separate movement and particularly in the event 95 of excessive load being imposed upon the device.

Positioned at a desired distance above the runners R and inwardly thereof is a pair of substantially transversely aligned heads or 100 castings 2. Each of the castings 2 is supported in desired position by a plurality of beams or irons 3. Each set or series of beams or irons 3 are preferably three in number with their lower extremities suitably anchored to the runner R and said

beams or irons are arranged upwardly in convergence. The upper end portion of each of the beams or irons 3 snugly fits within a socket 4 provided in the lower face of the 5 head or casting 2.

Resting upon the heads or castings 2 and rigidly held thereto by the clamps 5 or the like is a non-rotatable shaft 6. Loosely mounted upon the shaft 6 is a pair of longitudinally spaced winding members or wheels 7 and the periphery of each of said members or wheels 7 has disposed therearound in a conventional manner the teeth 8.

Interposed between the members or wheels 15 7 is a sleeve 9 surrounding the shaft 6 and having its opposite end portions suitably engaged with the hub portions 7^a of the members or wheels 7. It is preferred that the sleeve 9 be loosely engaged with the hub 20 portions 7^a in order to assure equal strain upon the members or wheels 7 as imposed thereupon by the driving member to be hereinafter more particularly referred to.

The forward beam or iron 3 of each runner R is connected by a transversely disposed rigid member or beam 10 and the opposite end beams or irons 3 are similarly connected by the rigid member or beam 11, the member or beam 11 being positioned at a predetermined point below the member or beam 10.

Secured to the forward member or beam 10 adjacent the opposite ends thereof are the substantially horizontally arranged and 35 rearwardly directed elongated plates 12 preferably metallic.

The rear end portion of each of the plates 12 is continued by a downwardly and inwardly inclined extension 14 suitably anchored to the adjacent member or beam 11.

15 denotes a driving shaft disposed transversely of the device and positioned below the stationary shaft 6. The shaft 15 is substantially in vertical alinement with the shaft 6 and the opposite end portions of the shaft 15 are rotatably supported by the bearings 16 mounted upon the plates 12. In the present embodiment of my invention, each of the bearings 16 is held to its plate 50 12 by the bolts 17 and each of which bolts is directed through an inwardly directed lug 18 carried by a head or casting 2. By this means the bolts 17 not only hold the bearings 16 in applied position, but also 55 serve as a support for the plates 12. By this arrangement it is also possible to raise or lower the plates 12 as the occasions of practice may necessitate and particularly to assure the proper mesh of the pinions 19 with 60 the teeth 8 of the members or wheels 7.

The pinions 19 are suitably keyed or otherwise fixed to the shaft 15 and are of a shrouded type. The flange 20 of one of the pinions 19 constitutes a ratchet gear with 65 which coacts the dogs or pawls 21 carried

by the power member or drum D. The power member or drum D is loosely mounted upon the shaft 15 and has independent rotation around said shaft in one direction but upon rotation in the opposite direction 70 said power member or drum D through the instrumentality of the dogs or pawls 21 and the ratchet teeth 20, rotates the shaft 15 with the resultant desired rotation of the winding members or wheels 7. The dogs or 75 pawls 21 are constantly urged toward the ratchet 21 by a spring 22 as is clearly illustrated in Fig. 2 of the accompanying drawings.

Clamped or otherwise fastened to the inner faces of the members or wheels 7 adjacent the hub portions thereof are the extremities of an endless flexible member M, preferably a cable. The stretches of the member or cable M pass below the sleeve 9 80 and the intermediate portion of said member or cable M is adapted to be suitably engaged with the stump to be extracted and preferably in connection with the hitch H. The particular construction of the hitch H 85 is embodied in a co-pending application executed on even date herewith.

Connecting the rear portions of the plates 12 is a rod 23 which serves to hold the plates 12 against relative lateral movement and 90 loosely mounted upon the rod 23 and in alinement with the drum D is a guide pulley 24.

A cable C or the like is adapted to be engaged with the member or drum D and 100 to extend therefrom beneath the pulley 24. The cable C is adapted to be fastened to a tractor or other source of power for creating the requisite operation of the device.

When strain is imposed upon the cable C, 105 the drum D will be caused to rotate in a direction resulting in an upward and rearward rotation of the members or wheels 7 so that the stretches of the member or cable M will be wrapped around the sleeve 9 110 from below. As the member or cable M wraps around the sleeve 9 through the medium of the members or wheels 7 sufficient strain will be imposed upon said member or cable M to extract the stump. 115

In initially engaging the member or cable M with the stump there must of necessity be a certain amount of slack and in order to take up this slack the power member or drum is brought into operation, the shaft 15 120 is initially rotated, preferably by a crank 25 and this rotation of the shaft 15 is independent of the power member or drum D and which is permitted through the medium of the coacting ratchet 20 and dogs or pawls 21 hereinbefore referred to. After the member or cable M has been rendered sufficiently taut, the power member or drum D is then rotated by desired pull upon the cable C.

In the use of a tractor or kindred sources 130

of power it often occurs, due to obstructions or to a limited path of travel, it is necessary to bring the tractor or the like to a standstill and to run the same back toward 5 the device. This return travel of the tractor or the like of necessity creates a slack in the cable C. In order to take up this slack the member or drum D can be manually rotated in the requisite direction, and which, 10 in the present embodiment of my invention, is done by direct engagement with the member or drum D. This retrograde movement of the member or drum D is independent of the members or wheels 7 and particularly 15 when said members or wheels 7 are sustaining a load. For this reason it is imperative that the members or wheels 7 be held against retrograde movement and in the present embodiment of my invention this is accomplished through the medium of the holding member coacting with each of the members or wheels 7. Each of the holding members as herein embodied comprises an elongated and substantially U-shaped member 26, 20 preferably formed of rod iron and having its free end portions loosely engaged with the beam or member 10 so that the said holding member may be readily swung into or out of engagement with a member or wheel 25 7 as the occasions of practice may require. The holding member 26 is normally maintained in engagement with the wheel or member 7 by gravity and the intermediate portion 26^a thereof is adapted to engage be- 30 tween adjacent teeth 8. The intermediate portion 26^a is arranged on such inclination as to permit unobstructed rotation of the member or wheel 7 in one direction and to effectively lock the same against movement 35 in the opposite direction.

In the embodiment of my invention as particularly illustrated in Figs. 7 and 8, the heads or castings 2^a are supported in substantially the same manner as has hereinbefore been disclosed with respect to the heads or castings 2. The stationary shaft 6^a supported by the heads or castings 2^a has loosely mounted thereon the winding member or drum 27 and an end portion of the 50 drum or winding member 27 is provided with a worm gear 28 with which engages the worm 29. The worm 29 is carried by a shaft 30 rotatably supported by the beams or members 10^a and 11^a, said shaft 30 extending in a direction longitudinally of the device. The shaft 30 has affixed to the end portion thereof a ratchet gear 31 with which coact the dogs or pawls 32 carried by the power member or drum D'. By this means 55 the shaft 31 may be readily rotated in one direction by the crank 25^a or the like to take up the initial slack in the member of cable M'. Coacting with the drum or power member D' is a cable C' herein disclosed 60 as extending beneath a guide pulley 33 suit-

ably engaged with a runner R'. The cable C' is adapted to be fixed to the tractor or other source of power as has heretofore been stated with respect to the cable C. It will also be understood that the power member 70 or drum D' can be independently rotated in one direction with respect to the shaft 30 to take up any slack which may occur in the cable C'.

From the foregoing description, it is 75 thought to be obvious that a stump puller constructed in accordance with my invention is particularly well adapted for use by reason of the convenience and facility with which it may be assembled and operated and 80 it will also be obvious that my invention is susceptible of some change and modification without departing from the principles and spirit thereof and for this reason I do not 85 wish to be understood as limiting myself to the precise arrangement and formation of the several parts herein shown in carrying out my invention in practice except as hereinafter claimed.

I claim:

1. A stump puller comprising a frame, a driving shaft supported thereby, a winding element rotatably supported by the frame and in driven connection with the shaft, a power drum loosely mounted upon 95 the shaft, coacting means carried by the shaft and the power drum whereby said drum and shaft rotate in unison upon movement of the drum in one direction, and means for rotating the shaft independently 100 of the drum.

2. A stump puller comprising a frame, a driving shaft supported thereby, a winding element rotatably supported by the frame and in driven connection with the 105 shaft, a power drum loosely mounted upon the shaft, coacting means carried by the shaft and the power drum whereby said drum and shaft rotate in unison upon movement of the drum in one direction, means 110 for rotating the shaft independently of the drum, said drum being freely rotatable upon the shaft in the opposite direction, and means for normally holding the winding element 115 against rotation in one direction.

3. A stump puller comprising a pair of spaced heads, means for supporting said heads, a stationary shaft supported by and secured to said heads, a winding element rotatably mounted on said shaft, a power 120 shaft in driving connection with the winding element, a drum mounted upon the power shaft and rotating the shaft upon rotation of the drum in one direction only, a power cable coacting with the drum, and 125 means for rotating the power shaft independently of the drum.

4. A stump puller comprising a pair of spaced heads, members engaged with said heads for supporting the same, a stationary 130

- shaft supported by the heads, plates supported by the members and spaced apart in the same general direction as the heads, a driving shaft rotatably supported by the 5 plates, a winding element carried by the stationary shaft and in driven connection with the driving shaft, and means coacting with the heads and the plates for adjusting said shafts one relative to the other.
- 10 5. A stump puller comprising a pair of spaced heads, members engaged with said heads for supporting the same, a stationary shaft supported by the heads, plates supported by the members and spaced apart in 15 the same general direction as the heads, a driving shaft rotatably supported by the plates, a winding element carried by the stationary shaft and in driven connection with the driving shaft, means coacting with the 20 heads and the plates for adjusting said shafts one relative to the other, said last

named means also constituting supports for the plates.

6. A stump puller comprising a pair of spaced heads, members engaged with said 25 heads for supporting the same, a stationary shaft supported by the heads, plates supported by the members and spaced apart in the same general direction as the heads, a driving shaft rotatably supported by the 30 plates, a winding element carried by the stationary shaft, means coacting with the heads and the plates for adjusting said shafts one relative to the other, said last named means constituting bolts engaged 35 with the heads and adjustably connected with the plates.

In testimony whereof I hereunto affix my signature in the presence of a witness.

CARL D. PACE.

Witness:

ROBERT A. BOSWELL.
